DESIGN FOR A SCARF COLLAR

Elizabeth Kasarda, New York, N. Y.

Application April 6, 1940, Serial No. 91,529

Term of patent 3½ years

To all whom it may concern:

Be it known that I, Elizabeth Kasarda, a citizen of the United States, residing at 5 East 98th Street, in the county of New York and State of New York, have invented a new, original, and ornamental Design for a Scarf Collar, of which the following is a specification, reference being had to the accompanying drawing, forming part thereof.

The figure is a front elevational view of a scarf collar showing my new design. The back of the collar is plain and straight across the bottom.

I claim:

The ornamental design for a scarf collar, substantially as shown and described.

ELIZABETH KASARDA.
